UNITED STATES PATENT OFFICE.

CORNELIUS B. CORCORAN, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,325,980.

Specification of Letters Patent. Patented Dec. 23, 1919.

Application filed September 26, 1918. Serial No. 255,741.

To all whom it may concern:

Be it known that I, CORMELIUS B. CORCORAN, a citizen of the United States, residing in borough of the Bronx, in the county 5 of the Bronx, city and State of New York, have invented certain new and useful Improvements in Type-Writing Machines, of which the following is a specification.

This invention relates to typewriting machines, and more particularly to improvements in means for actuating the case-shift mechanism.

It is found that objectionable features exist in connection with the ordinary arrangement of shift keys, one on each side of the keyboard. With the ordinary keys some difficulty exists in placing the finger properly thereon, and, in addition, application of considerable force is required to lift the platen and associated parts. Also placing the little fingers on said keys changes the positions of the hands from that which they ordinarily have with reference to the keyboard. Obviously it is desirable to provide means easily located, similar in that respect to the space bar, and adapted to be operated by some part of the hand capable of producing sufficient pressure without much effort. This invention can also be used in connection with keys other than the shift keys, and may cover devices operated by parts of the body other than the fingers or the palms of the hands. In order to obviate the defects noted above, I provide on each side of the machine a key having a dome-shaped head of considerable size, in position to be easily engaged by the palm of the hand. The improved keys are positioned so as to be engaged by the palms of the corresponding hands without disturbing to any great extent the positions of the fingers with reference to the keyboard.

Other features and advantages will hereinafter appear.

45 In the accompanying drawings,

Figure 1 is a sectional view in elevation of an Underwood typewriting machine with the present invention applied thereto, the platen being in normal or lower-case position.

Fig. 2 is a fragmentary perspective view showing the relative position of some of the parts while writing in upper-case, the normal position of the shift key being indicated in dot-and-dash lines.

Fig. 3 is a perspective view on a larger scale of the attachment secured to the frame on the inside, the frame being shown partly in section.

Fig. 4 is a front elevation of the attachment and the adjoining parts of the machine, the frame and shift key being shown in section.

In the Underwood typewriting machine, keys 6 are connected to type-bars 7, through 65 interponents 8, to cause types 9 to print characters on a work-sheet carried on platen 10.

Carriage 11, mounted to slide on rods 12 and 13, carries platen 10 which, however, is 70 supported in a frame 14, mounted for vertical movement in carriage 11. Connected with frame 14 is a wheel 15, resting on rail 16 attached to frames 17 supported on shaft 18. Shift keys 19 are mounted on the usual 75 key levers 20 having upwardly projecting arms 23, and held with their notched ends in engagement with rod 21 by means of springs 22. Upon depression of either key 19, the corresponding arm 23 will press 80 against one of the frames 17, and, by swinging rail 16 about shaft 18, will lift the platen into position for upper-case printing. The parts thus far described are substantially those known in the art.

85 The present invention relates to a device for facilitating the operation of the usual case-shift mechanism, and may be made part of the machine as originally constructed, or may be in the form of an attachment to a 90 machine of one of the usual types. Obviously this device can be used on one or both sides of the machine as desired. In the present embodiment, the device includes a carrying plate or bracket 24 secured to one 95 of the side frames 25 by means of screws 26 passing through apertures in clamping plates 27 and engaging screw-threaded openings in said plate 24. Upon the plate 24 is pivoted, by means of a screw 28, a lever 29 100 on one end of which is a dome-shaped head 30 adapted to be engaged by the palm of the corresponding hand. At the other end of lever 29 is mounted a pin 31 which engages a slot in one end of a second lever 32. At 105 the other end of lever 32 is a pin 33 overlying key lever 20. It is evident that upon depression of dome-shaped head 30, pin 33 will depress key lever 20 and cause actuation of the case-shift mechanism.

Variations may be resorted to within the scope of the invention, and portions of the improvements may be used without others.

Having thus described my invention, I claim:

1. A special key-attachment for a type-writing machine, including a frame, a key-board, and a special operating key, comprising, in combination, a bracket, friction clamping means for attaching said bracket to a part of the machine frame, and a lever system comprising mutually coöperative levers mounted on said bracket, one of said levers having an operating element overlying a portion of the special key, and another of said levers having a dome-shaped portion conveniently located for contact by a portion of the hand other than the digits thereof, so that the special key may be operated by depression of said dome-shaped portion, without removing any of the digits of the hand from their operating position over the keyboard.
2. A special key-attachment for a type-writing machine, including a frame, a key-board, and a special operating key, comprising, in combination, a bracket, friction clamping means for attaching said bracket to a part of the machine frame, and a pair of levers pivotally mounted on said bracket, the adjacent arms of said levers being connected by a pin-and-slot connection, the free end of one of said levers having an operating element overlying a portion of the special key, and the free end of the other lever having a dome-shaped portion conveniently located for contact by a portion of the hand other than the digits thereof, so that the special key may be operated by depression of said dome-shaped portion, without removing any of the digits of the hand from their operating position over the keyboard.

CORNELIUS B. CORCORAN.
